CLAIM

The ornamental design for a display panel of medical X-ray photographing apparatus with graphical user interface, as shown and described.

DESCRIPTION

FIG. 1 is a front view of a display panel of medical X-ray photographing apparatus with graphical user interface of the present design;

FIG. 2 is a rear view thereof;

FIG. 3 is a left side view thereof;

FIG. 4 is a right side view thereof;

FIG. 5 is a top view thereof;

FIG. 6 is a bottom view thereof; and,

FIG. 7 is an enlarged view of 7-7 portion of FIG. 3 thereof. The broken lines shown in the drawings represent portions of display panel of medical X-ray photographing apparatus with graphical user interface that form no part of the claimed design. The long dashed and short dashed lines indicate only boundaries of the claimed subject matter and form no part of the claimed design.

1 Claim, 6 Drawing Sheets
